UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR.

1,342,095.

Specification of Letters Patent.

Patented June 1, 1920.

Application filed October 24, 1919. Serial No. 333,044.

To all whom it may concern:

Be it known that I, ARGYLE CAMPBELL, a citizen of the United States, residing at Chicago, in the county of Cook and State 5 of Illinois, have invented a certain new and useful Improvement in Cars, of which the following is a full, clear, concise, and exact description, reference being had to the accompanying drawings, forming a part of 10 this specification.

This invention relates to improvements in cars.

As is well known, cars employed in the carrying of ore and used on ore docks for 15 discharging into bins that in turn deliver the ore to the boats, are made comparatively short and are provided with a single dumping opening in the bottom. The single dumping opening is necessitated because of 20 the standardized dimensions and spacing of the bins of the ore docks and ore boats and the consequent necessity of spotting the ore cars properly on the dock before discharging the ore. Because of the limitation to a single 25 opening in the bottom of such ore cars, it is highly essential that the opening be made as large as possible in order to prevent "bridging" of the ore in the car and also to insure as speedy discharge of the ore as possible. 30 One object of my invention is to provide an improved car particularly designed for use in the ore carrying service and wherein the car is provided with a discharge opening at the bottom thereof of relatively great 35 area.

Another and more specific object of the invention is to provide a discharge opening for cars of the type indicated which is closed by two sets of doors swinging about axes at 40 right angles to each other and wherein one set of the doors is primarily operated and said set of primarily operated doors serves to close and hold in closed position, the doors of the other set.

45 The invention furthermore consists in the improvements in the parts and devices and in the novel combinations of the parts and devices herein shown, described and made the subject matter of claims.

50 In the drawings forming a part of this specification, Figure 1 is a side elevation of a car embodying my invention. Fig. 2 is an enlarged vertical transverse sectional view of the car shown in Fig. 1 and taken substantially on the lines 2-2 thereof.

Fig. 3 is a horizontal sectional view and part top plan, the section corresponding to the line 3-3 of Fig. 2. Fig. 4 is a longitudinal sectional view taken substantially on the line 4-4 of Fig. 2. And Fig. 5 is a 60 partial longitudinal sectional view taken substantially on the line 5-5 of Fig. 2.

In said drawings, the car is shown of that type such as commonly employed in the ore carrying service, the same having a single 65 hopper and the over-all length of the car being relatively short, approximating twenty-four feet. The car is shown as having side walls 10. These are extended downwardly and secured to the outer flange of the Z-bar 70 side sill indicated at 12. On each side of the car, inwardly and downwardly inclined side sheets 11 are employed as indicated most clearly in Fig. 2, the lower edges of said sheets 11 being secured to the inner 75 flanges of the Z-bar side sills 12. The single hopper also has sloping end walls indicated at 13-13 in Fig. 5 and it will be noted that the lower edges of the inclined end walls 13 and inclined parts of the side 80 sheets 11 terminate at a point approximately on a level with the top of the short center or draft sills 14-14 on each end of the car. Said sills 14 are preferably of channel shape 85 and are cut off at their inner ends as indicated at 15 so as to avoid passing through the discharge opening of the car and leaving the latter completely uninterrupted to facilitate the discharge of ore or other material. The discharge opening of the car 90

is closed by two sets of doors, each set comprising a pair of pivotally mounted doors. One set includes the two pivoted bottom doors A-A and the other set includes the pivoted doors B-B. The doors A-A are 95 pivoted along their outer longitudinally extending edges as indicated at 16-16 to hinge butts 17-17 secured to the under side of the Z-bars 12. The doors A-A are comprised preferably of sheet metal suitably reinforced 100 on their under sides by longitudinally extending braces 18 and transversely extending braces 19. The inner edges of the doors A-A are curved as indicated at 20 so as to provide a wedging joint when the doors 105 A-A are in closed position.

The doors A-A are directly or primarily operated by the following mechanism. Extending transversely of the car near one end thereof and beneath the corresponding end 110

hopper sheet 13, is an operating shaft 21. The latter is provided at the center thereof with a hub 22 to which is pivoted a link 23. Pivots connected to the link 23 is 5 another link 24 from which extends on opposite sides thereof a bar 25. To the opposite ends of the bar 25 are pivotally connected hook-shaped heavy links 26, the latter in turn being pivotally connected by means of 10 links 27 to the extended ends 28-28 of the respective bars 18 on the doors A—A. The linkages described are of that form wherein the shaft is relieved of torsional strain when the doors are in closed position, the load 15 being transferred to the shaft in such way as to impose merely a bending and shearing strain thereon.

Near one end of the shaft 21 but inside of the corresponding side wall 10 of the 20 car, the shaft has secured thereto another hub 29. Pivots connected to the latter is a link 30 which in turn is pivotally connected to a short link 31. A hook-shaped link 32 is pivotally attached to the link 31 25 and from the link 32 extends an adjustable turn-buckle link 33. From the end of the link 33 extends a chain 34 which is secured to a sheave wheel 35 carried at the outer end of a transversely extending auxiliary shaft 36. Said shaft 36 is suitably mounted in 30 bearings provided by one of the side wall sheets of the car and in upstanding bearing brackets 37 carried by the center sills. A cover plate 38 joins the bearing brackets 37 35 and is adapted to shield the sheave wheels 39-39 carried by said shaft between the brackets 37. Two of said sheave wheels 39 are provided, from each of which extends a chain indicated conventionally at 40 in Fig. 40 5. The lower ends of said chains 40 are connected to the corresponding extended ends 28 of the braces 18 carried by the doors A—A.

The main operating shaft 21 is provided 45 at each outer end thereof with a ratchet wheel 41 and with said ratchet wheels 41 are adapted to coöperate locking dogs 42. In order to be able to operate the door mechanism from either side of the car, an 50 auxiliary shaft 43 is extended transversely of the car, the latter at each end thereof having an operating handle 44 and pivotally connected to the operating handles 44 and corresponding dogs 42 are links 45. 55 As will be understood by those skilled in the art, manipulation of either handle 44 on either side of the car will release both dogs 42 simultaneously and consequently permit rotation of the main operating shaft 21.

60 Assuming the parts in the position shown in the drawings, rotation of the shaft 21 in a clockwise direction will unwind the linkages immediately adjacent thereto. Similarly, the links 30, 31 and 32 will unwind 65 from the shaft 21 which will permit the chain

34 to wind about the sheave wheel 35. This in turn permits the chains 40 to unwind from the sheave wheels 39 so that the opening and closing movements of the doors A—A are uniform at each end.

The doors B—B are pivotally connected along their upper edges as indicated at 46 to hinge brackets 47 secured to braces 48 that extend transversely of the car and serve to connect the ends of the cut off center 75 sills with the end sheets 13 of the car hopper. The doors B, as clearly shown in Fig. 5, form continuations of the end hopper sheets 13 when the doors B—B are in closed position and are adapted to swing toward 80 the ends of the car about transverse axes, as will be understood from an inspection of Fig. 5. The outward swinging movement of said doors B—B is limited by stops 49 secured to the center sills 14. The doors 85 B—B are braced on their under sides by Z-bars or other suitable braces 50. The doors B—B are operated by means carried on the doors A—A so as to eliminate expensive operating mechanism and mechanism which 90 would be likely to get out of order. To operate the doors B—B, the extended ends 28 of the respective doors A—A, at each end of the latter, are provided with wedge shaped camming members 51—51, preferably made in the form of plates or castings and riveted to the braces 18—18 of the doors A—A. Said cam wedges 51 are so located as to engage the under sides of the braces 50 carried by the doors B—B so that, as the 95 doors A—A move upwardly toward closed position, the cam wedges 51 will engage the braces 50 and gradually force the doors B—B to closed position as the doors A—A reach closed position. As will be understood, the stops 49 for the doors B—B are so adjusted and the camming wedges 51 so positioned that the doors B—B will be permitted the necessary opening swinging movement but at the same time leave them 100 in such a position as to insure the camming wedges 51 properly engaging the braces 50.

As an additional means for holding the doors B—B in closed position, the doors A—A, near the outer ends thereof, are provided with castings 52—52 having upturned inclined fingers 53 which engage the under sides of the doors B—B just at the final closing movement and effectively hold the doors B—B in closed position, particularly 115 near their ends.

With the arrangements shown, it is evident that I obtain a relatively great opening area, the same in fact being longer than the distance between the inner wheels of the 120 trucks and wider than the distance between the rails. Furthermore, the operating mechanism is extremely simple and in reality only one mechanism is primarily employed for operating the doors A—A, the 130

doors B—B being closed by means carried on the doors A—A. This latter arrangement insures that the doors A—A and B—B will reach closed position at the proper time and there can be no danger of one set of doors being properly closed and the other set improperly closed at the same time.

I claim:

1. In a car having a centrally disposed bottom opening, the combination with a pair of longitudinally arranged doors pivotally mounted to swing about axes extending lengthwise of the car; of a pair of end doors pivotally mounted to swing about axes extending transversely of the car; mechanism for primarily closing one of said pairs of doors; and means, carried by said pair of primarily operated doors, for closing the other pair of doors.
2. In a car having a centrally disposed bottom opening, the combination with a pair of longitudinally arranged doors pivotally mounted to swing about axes extending lengthwise of the car; of a pair of end doors pivotally mounted to swing about axes extending transversely of the car; mechanism for opening and closing said longitudinally arranged pair of doors; and means carried by said longitudinally arranged doors for closing the end doors.
3. In a car having a centrally disposed bottom opening, the combination with a pair of longitudinally arranged doors pivotally mounted to swing about axes extending lengthwise of the car; of a pair of end doors pivotally mounted to swing about axes extending transversely of the car, mechanism for primarily closing one of said pairs of doors; and means, carried by said pair of primarily operated doors, for closing the other pair of doors, said means comprising wedging elements engageable with the under faces of the last mentioned pair of doors.
4. In a car having a centrally disposed bottom opening, the combination with a pair of longitudinally arranged doors pivotally mounted to swing about axes extending lengthwise of the car; of a pair of end doors pivotally mounted to swing about axes extending transversely of the car; mechanism for opening and closing said longitudinally arranged pair of doors; and means carried by said longitudinally arranged doors for closing the end doors, including wedges carried by the longitudinally arranged doors

adapted to engage the under faces of the end doors.

5. In a car having a centrally disposed discharge opening, the combination with a pair of pivotally mounted longitudinally extending doors; of a pair of pivotally mounted transversely extending end doors; means for limiting the opening movement of said end doors; mechanism for closing and opening said longitudinally extending doors; and means carried by the longitudinally extending doors for engaging the transverse end doors to cam the latter to closed position.

6. In a car having a centrally disposed bottom opening, the combination with a pair of longitudinally arranged doors pivotally mounted to swing about axes extending lengthwise of the car; of a pair of end doors pivotally mounted to swing about axes extending transversely of the car; mechanism for primarily closing one of said pairs of doors; means, carried by said pair of primarily operated doors, for closing the other pair of doors; and fingers carried by said pair of primarily operated doors for engaging the free edges of the other pair of doors when both sets of doors reach closed position.

7. In an ore car having a central single hopper and center sills terminated outside of the ends of the hopper, the combination with a pair of longitudinally extending doors adapted to swing about their outer longitudinal edges; of a pair of end doors pivotally mounted to swing about their upper transversely extending edges; a transversely extending operating shaft; mechanism interposed between said shaft and the longitudinally extending doors for operating the latter; means for limiting the opening movement of said transversely extending doors; and camming wedges carried by the longitudinally extending doors for engaging the under sides of the transversely extending doors to force the latter to closed position when the longitudinally extending doors are moved to closed position.

In witness that I claim the foregoing I have hereunto subscribed my name this 3rd day of Oct., 1919.

ARGYLE CAMPBELL.
